UNITED STATES PATENT OFFICE.

EDGAR JEROME HOFFMAN, OF AKRON, OHIO.

HANGER.

1,352,895.

Specification of Letters Patent. Patented Sept. 14, 1920.

Application filed May 20, 1920. Serial No. 382,859.

To all whom it may concern:

Be it known that I, EDGAR J. HOFFMAN, a citizen of the United States, residing at Akron, in the county of Summit and State 5 of Ohio, have invented a new and useful Hanger, of which the following is a specification.

The present invention relates to hangers, or conduit supports, and more particularly 10 to devices of this character which may be readily and easily applied to I beams or the like.

An object of this invention is to provide a device of this character which may be adjusted to various widths, thus adapting the 15 device for use in connection with I beams of various sizes.

A further object of the invention is the provision of means carried by the support 20 for accommodating a conduit, the means being curved to conform to the curvature of a conduit, thereby insuring against lateral movement of the conduit, with relation to its support.

With the foregoing and other objects in view which will appear as the description proceeds, the invention resides in the combination and arrangement of parts and in the details of construction hereinafter more 30 fully described, it being understood that changes in the precise embodiment of the invention herein disclosed, may be made within the scope of what is claimed, without departing from the spirit of the invention.

Referring to the drawing:—

Figure 1 illustrates a plan view of a support constructed in accordance with the present invention.

Fig. 2 illustrates a side elevational view 40 of the same; and

Fig. 3 illustrates a sectional view taken on line 3—3 of Fig. 2.

Referring to the drawing in detail, the hanger forming the subject matter of the 45 present invention, includes the opposed clamping sections 5 and 6, each of which comprises a pair of arms 7, which have their respective outer ends bent upwardly as at 8, and inwardly as at 9, the portion 9 of 50 each arm lying in spaced relation with the body portion of the arm.

The inner extremity of each of the arms extends downwardly as at 10 and inwardly as at 11, the inwardly extending portion 11 55 of each arm, also lying in spaced relation with the body portion thereof, and as shown

these portions 10 of the arms are apertured to accommodate the securing bolts 12, which connect the opposed sections and provide means for permitting the sections to be adjusted with relation to each other to permit the hanger to be applied to various sized I beams.

The arms 7 of each pair, are connected adjacent the outer or free ends thereof by 65 means of the supporting member 13, which are formed integral with the arms 7, the central portions of the supporting members being curved to conform to the curvature of the usual conduit now in use.

It might be further stated that if it is desired one of the clamping sections may be employed independently of the other, in which case the relatively straight end portions of the arms 7 may be bent upwardly 75 over the I beam, thus eliminating the bolts 12 in the accomplishment of the securing of the sections to the I beam. It is of course understood that the above mentioned form is only employed with relatively light conduits.

In the use of the device, the hook portions formed by the portions 8 and 9 of the arms 7 are positioned over a portion of an I beam as indicated by Fig. 2 of the drawing, 85 whereupon the securing bolts 12 are manipulated to move the sections toward each other, so that the device will be clamped into engagement on the I beam.

Having thus described the invention, what 90 is claimed as new is:—

A conduit hanger including opposed sections, each of said sections comprising a pair of spaced arms, a curved supporting member connecting the arms of each pair, said 95 arms having upwardly extending hook members formed integral with one end thereof, each of said arms having a depending flange, the flanges of one pair of arms being disposed in spaced relation with the flanges 100 of the opposed arms, said flanges being provided with openings, and means disposed in the openings and contacting with the outer surfaces of the flange for securing the sections together.

In testimony that I claim the foregoing as my own, I have hereto affixed my signature in the presence of two witnesses.

EDGAR JEROME HOFFMAN.
